UNITED STATES PATENT OFFICE.

JOHN LLOYD WRIGHT, OF CHICAGO, ILLINOIS.

DESIGN FOR A GAME-PLAYING PIECE.

50,116.

Specification for Design.

Patented Dec. 26, 1916.

Application filed September 25, 1916. Serial No. 122,173. Term of patent 7 years.

To all whom it may concern:

Be it known that I, JOHN LLOYD WRIGHT, a citizen of the United States, and a resident of Chicago, in the county of Cook and State of Illinois, have invented a new, original, and ornamental Design for Game-Playing Pieces, of which the following is a specification, reference being had to the accompanying drawing, forming part thereof.

On the drawing the figure is a perspective view of the piece representing a hobbyhorse with a man shown mounted thereon.

I claim:

The ornamental design for a game-playing piece, as shown and described.

JOHN LLOYD WRIGHT.
